UNITED STATES PATENT OFFICE

120,751

DESIGN FOR A CIGARETTE ROLLER

James H. Fuller, University City, Mo., assignor to Marshall D. Gibson, Webster Groves, Mo.

Application September 25, 1939, Serial No. 87,378

Term of patent 14 years

To all whom it may concern:

Be it known that I, James H. Fuller, a citizen of the United States, residing at University City, St. Louis county, State of Missouri, have invented a new, original, and ornamental Design for a Cigarette Roller, of which the following is a specification, reference being had to the accompanying drawing, forming part thereof.

Fig. 1 is a perspective view of a cigarette roller from the front and side, showing my new design; and

Fig. 2 is a perspective view from the rear and side.

I claim:

The ornamental design for a cigarette roller, as shown.

JAMES H. FULLER.
